US00D921134S

(12) **United States Design Patent** (10) **Patent No.:** **US D921,134 S**
Jaquish et al. (45) **Date of Patent:** **** Jun. 1, 2021**

(54) **EXERCISE APPARATUS**

- (71) Applicant: **Jaquish Biomedical Corporation**,
 Nevada City, CA (US)
- (72) Inventors: **John Paul Jaquish**, Nevada City, CA
 (US); **Paul Edward Jaquish**, Nevada
 City, CA (US); **Henry David Alkire**,
 Nevada City, CA (US)
- (73) Assignee: **Jaquish Biomedical Corporation**,
 Nevada City, CA (US)
- (**) Term: **15 Years**
- (21) Appl. No.: **29/721,690**
- (22) Filed: **Jan. 22, 2020**

Related U.S. Application Data

- (63) Continuation of application No. 29/681,204, filed on
 Feb. 22, 2019, now Pat. No. Des. 914,113.
- (51) **LOC (13) Cl.** **21-02**
- (52) **U.S. Cl.**

Primary Examiner — Cynthia Ramirez*Assistant Examiner* — Michael A Maharajh(74) *Attorney, Agent, or Firm* — Morgan, Lewis & Bockius LLP(57) **CLAIM**

The ornamental design for an exercise apparatus, as shown and described.

DESCRIPTION

FIG. 1 is a perspective view of an exercise apparatus showing our new design;

FIG. 2 is a front view, the back view is a mirror image thereof;

FIG. 3 is a top view thereof;

FIG. 4 is a bottom view thereof; and,

FIG. 5 is a side view, the opposite side view is a mirror image thereof.

The band is shown with a symbolic break in its length. The appearance of any portion of the article beyond the break lines forms no part of the claimed design.
